UNITED STATES PATENT OFFICE.

HAROLD I. PRATT, OF GLEN COVE, NEW YORK, ASSIGNOR TO THE INTERNATIONAL COMMITTEE OF THE YOUNG MEN'S CHRISTIAN ASSOCIATIONS, OF NEW YORK, N. Y., A CORPORATION OF NEW YORK.

DESIGN FOR A PIN, BRASSARD, OR BADGE.

53,748.

Specification for Design.

Patented Aug. 26, 1919.

Application filed January 25, 1919. Serial No. 273,181. Term of patent 14 years.

To all whom it may concern:

Be it known that I, HAROLD I. PRATT, a citizen of the United States of America, residing at Fresh Pond Lane, Glen Cove, Long Island, in the State of New York, have invented a new, original, and ornamental Design for Young Men's Christian Association Pin, Brassard, or Badge, of which the following is a specification, reference being had to the accompanying drawing, forming part thereof.

The drawing shows my design having a plain field, a shaded border, a shaded triangle extending across the plain field and edges differently shaded to the border.

I claim:

The ornamental design for a pin, brassard, or badge, as shown.

HAROLD I. PRATT.
